ATTORNEY

UNITED STATES PATENT OFFICE

MAX LEDERMAN, OF NEW YORK, N. Y.

GARTER

Application filed August 23, 1928. Serial No. 301,597.

This invention relates to garters, and has for an object to provide an improved construction wherein an ample support is provided for a hose without causing an undesirable 5 pinching of the leg.

Another object of the invention is to provide a hose supporter, wherein a plurality of clamps or supporting members are connected with the hose in order to provide support 10 points at distant points.

A further object is to provide in a garter, a hose supporting band with connecting means for connecting the same with a hose, and upwardly-extending elastic members disengaging 15ably connected with the shirt, whereby the garter will act to support hose and hold the shirt of the wearer against rising.

In the accompanying drawings,—

Figure 1 is a perspective view of a garter 20 made according to the present invention, the same being illustrated on a figure;

Figure 2 is an enlarged perspective view of the garter shown in Figure 1;

Figure 3 is a perspective view showing a 25 pair of garters in position with portions engaging the lower part of the shirt and portions engaging stockings, whereby the stockings are supported and the shirt is held against rising;

Figure 4 is an enlarged plan view of one of the shirt-holding members.

Figure 5 is an edge view of the structure shown in Figure 2 but with one of the shirt-holding members applied thereto.

Referring to the accompanying drawing, by numerals, 1 indicates a substantially rectangular body of cloth having concave sides and 2 an encircling strap. The body 1 may be made from fabric of any desired kind and 40 the encircling strap 2 is preferably elastic with one end stitched or otherwise rigidly secured to body 1 at point 3. The free end of strap 2 is provided with a well-known form of fastening loop 4 having a restricted portion 5 adapted to receive the stud 6 of the fastener 7. The fastener 7 is metal and is stitched or otherwise rigidly secured to body 1. Depending hose engaging members 8 and 9 are stitched or otherwise rigidly secured to the 45 lower edge of body 1, said hose-engaging

members being of a desired structure, preferably an ordinary loop 10 and stud 11, as now found on the open market. These members are caught into or interlocked with the hose, as shown in Figures 1 and 3, so that when strap 2 is arranged as shown in Figure 1, the body 1 will provide a proper support for the hose. In many cases it is desired to not only support the hose properly, but to hold the shirt of a person from rising, particularly when wearing a belt. In order to secure this result, a shirt-retaining strap 12 is connected with the stud 6 and also with the stud 13. Each strap is provided with a loop 14 having a reduced portion 15 adapted to fit over the stud on body 1. The strap is looped through the loop 14 and is held in adjusted position by suitable buckle 16, whereby the effective length of strap 12 may be varied.

The shirt-engaging structure 17 is connected to the opposite end of strap 12 to loop 14, said shirt-engaging member being similar to members 9 and 10. This member is provided with the usual stud 18 and loop 19, which interlock with the shirt in a similar manner to the way members 9 and 10 interlock or pinch the hose. By forming the body 1 of appreciable length members 9 and 10 are on opposite sides of the leg, and thereby

provide a more even support than where only one supporting member is used. Also, this arrangement permits the straps to be connected to studs 6 and 13 on opposite sides of the leg, so that a proper distributed supporting group of straps may be provided for the shirt.

By reason of the fact that the straps 12 may be readily disengaged by studs 6 and 13, the lower part of the garter, namely, body 1, members 2, 9 and 10, may be used as hose supporter only. Also by providing the body 1 of appreciable width, as well as length, easy contact is made with the leg, so that none of the parts have a tendency to pinch. As the straps 12 are elastic they will readily give as a person using the device bends, but when released the shirt will be gradually pulled back to its original position.

What I claim is:—

A garter, including a substantially rectangular body of cloth having concave sides, a

stud connected with said body near each of two of the corners of the body, hose supporting members connected to the opposite corners of the body, an encircling band connected to one corner of the body and disengageably connected to the stud at the opposite corner, and a shirt-holding member connected to each of said studs, extending in an opposite direction to the hose supporting members, each of said shirt-holding members having means for gripping part of the shirt, for preventing the shirt from moving upward.

Signed at New York in the county of New York and State of New York this 22nd day of August A. D. 1928.
